UNITED STATES PATENT OFFICE.

ABRAHAM BASSFORD, OF MILLWOOD, NEW YORK.

ADJUSTABLE-TENNIS-NET POST.

Application filed August 5, 1926. Serial No. 127,377.

This invention relates to a fastening device and more particularly to a device to fasten the ends of a tennis net or the like.

It is an object of the invention to produce an improved, simple, efficient and inexpensive device for tennis posts through the medium of which the tennis net can be raised or lowered so as to permit an adjustment of the net for singles or doubles play.

It is another object of the invention to produce a device to be used in connection with tennis net posts to permit the net to be raised or lowered with great ease and celerity, and without the necessity of disturbing the setting of the net.

It is a further object of the invention to produce a tennis post which can be easily set up or removed and which will permit the tennis net to be raised or lowered without disturbing the setting of the net.

Other and further objects and advantages of the invention together with its distinguishing features will appear as the specification proceeds, of which the accompanying drawings form a part: which drawings, it is understood, illustrate but one example or embodiment of the invention to which I do not limit myself, for the same manifestly, can be easily changed or varied without in the least departing from the spirit of the invention.

Referring to said illustrated embodiment:

Figure 1 is a side elevation of a tennis post embedded in a post base with the device for raising or lowering the net affixed to the top thereof;

Figure 2 is a view showing a longitudinal cross-section, the device for raising and lowering the net affixed to the top of the post; and

Figure 3 illustrates a modification of the device as shown in Figure 2.

In tennis playing many times it is necessary to change the height of the tennis net, which is at the present accomplished by means of pulling a rope or a similar device. It is a well known fact that the raising or lowering of the net by slackening the tension thereof is not a desirable one for a slack generally causes a sag in the center of the net making the clearance line on the top of the net curved. Furthermore, no matter how careful or how hard it is tried a net which is raised or lowered by means of a rope and pulley cannot be finely

adjusted, and the adjustment is usually very cumbersome.

With the aid of my device the net can be easily adjusted at various heights at any time, and can be maintained at the same tension without any difficulty as it will appear from the description hereafter.

Referring to the drawings I have shown by way of illustration a tennis net 10 fastened to a post 11 at 12 and 13. It is understood that a similar fastening of the net is effected at the other side thereof which is not shown.

The post 11 snugly fits into a tubular receptacle 14 which is embedded in a concrete base 15 set in the ground. The net 10 is fastened at the top of a turn buckle 16 which has one end thereof fastened to the net 10 and the other fastened to the eye 17 in the bracket member 19. This bracket member 19 has a shank 20 formed with a collar 21 and fixed to it by a pin 22. The post 11 has a cap 23 secured to it by means of a driving fit as indicated by the reference character 24 in Figure 2.

A modification of this device is illustrated in Figure 3 wherein to the post 11 is affixed the cap 23 by means of threads 24'. Another feature is that the shank 20 is threaded into the bracket 19 as shown at 25. Also in this modification, the collar 21 is screwed to the shank 20 by means of a screw 22'.

The upper end of the net is secured to the post 11 through the medium of the turn-buckle 16, and by tightening or loosening the tension of the net, by turning the turn-buckle, the bracket 19 may be raised from a lower position to a higher position as indicated by the dotted lines in Figure 2. The pull of the net on the bracket 19 causes the shank 20 to move slightly out of the perpendicular and impinge upon the edges 26' and 26'' of the opening 26 in the cap 23. The shank 20 may be of any length, depending upon the variation in height that is desired to move the net. When the bracket 19 is in a raised position, or away from its lowermost position, it can be lowered by simply tapping with the hand or a mallet on the top of the bracket, but when it is desired to be raised the turn-buckle is loosened and the bracket raised to the desired height, tightening the turn-buckle after the adjustment has been made.

The way the shank 20 impinges against

the walls of the cap 23 is shown in Figure 2 by the dotted lines.

It will be understood that the post 11 herein shown as tubular may be of any configuration such as square, hexagonal etc., as well as the cap 23 and the bracket 19 with the shank 20, as long as the opening 26 has enough play between the shank 20 and the edges 26' and 26'' to permit of the shank 20 to be thrown out of perpendicular alignment with the post 11 and thereby causing the shank 20 to impinge against the opening 26, as heretofore described.

It goes without saying that if the post is otherwise than round as illustrated, the socket 14 may likewise be configured to correspond with the configuration of the post.

It is thus seen that by means of my improved device, whenever it is desired to raise or lower the net the same may be effected with speed and without difficulty.

I would state in conclusion that while the illustrated and described examples constitute one practical embodiment of my invention, I do not limit myself strictly to the exact details herein illustrated, since, manifestly, the same can be considerably varied without departure from the spirit of the invention as defined in the appended claims.

Having thus described my invention, I claim:

1. An adjustable post comprising a body portion, a plate carried transversely thereof, said plate being apertured, an adjustable bracket member mounted on the post and including a shank slideable in the plate aperture, the shank being slightly smaller in dimension than the aperture whereby force applied to the bracket member in a direction

transverse to the shank functions to bind or pinch the shank within the aperture of the plate.

2. An adjustable post comprising an elongated body portion, a plate mounted transversely thereof, said plate being apertured, a shank mounted therein and freely slideable longitudinally of the post, an abutment carried by the shank to limit its sliding movement in one direction, and a bracket carried by the other end of the shank to limit its movement in the opposite direction, said shank being capable of slight lateral movement within the plate aperture under action of a force applied to the bracket member transversely of the post whereby to bind or pinch the shank within the plate aperture.

3. An adjustable post comprising a body portion, a cap-plate therefor, said plate being provided with an aperture, a bracket member mounted upon the upper end of the post and including a shank slideable through the aperture in the plate to effectively vary the overall length of the post, said shank and plate aperture being dimensioned to permit slight lateral movement of the shank under the action of a force applied to the bracket transversely of the post whereby to bind or pinch the bracket shank within the plate at any desired degree of extension.

4. The apparatus described in claim 3, wherein the body of the post is hollow immediately adjacent to the cap-plate whereby to provide a housing for the bracket shank.

5. The apparatus described in claim 3, wherein the bracket shank carries a collar at its inner end for limiting the range of extension thereof with respect to the post.

A. BASSFORD.
